UNITED STATES PATENT OFFICE

154,611

DESIGN FOR AN AUTOMOBILE INSTRUMENT PANEL

Robert J. Lauer, Huntington Woods, Mich., assignor to General Motors Corporation, Detroit, Mich., a corporation of Delaware

Application February 18, 1948, Serial No. 144,580

Term of patent 3½ years

(Cl. D52—1)

To all whom it may concern:

It is known that I, Robert J. Lauer, a citizen of the United States, residing at Huntington Woods, in the county of Wayne and State of Michigan, have invented a new, original, and ornamental Design for an Automobile Instrument Panel, of which the following is a specification, reference being had to the accompanying drawing, forming part thereof.

The figure is a perspective view of an automo-

bile instrument panel, showing my new design.

I claim:

The ornamental design for an automobile instrument panel, as shown.

ROBERT J. LAUER.
